UNITED STATES PATENT OFFICE.

JOSEPH J. MORRIS, OF HARRISBURG, ILLINOIS.

MACHINE FOR MAKING BITS.

1,123,350.

Specification of Letters Patent.

Patented Jan. 5, 1915.

Application filed December 26, 1913. Serial No. 808,893.

To all whom it may concern:

Be it known that I, JOSEPH J. MORRIS, a citizen of the United States, residing at Harrisburg, in the county of Daline and 5 State of Illinois, have invented a new and useful Machine for Making Bits, of which the following is a specification.

This invention relates to machines for producing steel bits such as used in mining 10 machines or coal cutters, one of the objects of the invention being to provide a roller die coöperating with a fixed die whereby during the actuation of the parts, a blank supplied to the machine will be provided 15 with the desired shape.

A further object is to provide a machine of this character utilizing improved means for feeding blanks into position for engagement by the movable die, there being an adjustable stop for limiting such feeding 20 movement of the blank.

A further object is to provide improved means whereby the actuation of the movable die is effected, said means being constantly 25 under the control of the operator.

Another object is to provide a machine of this character whereby bits which have spread as a result of use, can be readily reshaped and sharpened.

30 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a side elevation of the machine. Fig. 2 is a rear elevation thereof, a portion being broken away. Fig. 3 is an enlarged vertical section through the coöperating dies and showing a blank upon the stationary die and against the gage. Fig. 4 is a plan view of the feed mechanism, the adjacent parts of the plunger and standard of the machine being shown in section. Fig. 5 is a perspective view of one form of fixed die which may be used. Fig. 6 is a perspective view of an-

other form of fixed die which can be used in connection with the machine. Fig. 7 is a transverse section through another modified form of die particularly designed for use in connection with old bits to be reshaped or resharpener. Fig. 8 is a section on line A—B Fig. 7.

Referring to the figures by characters of reference 1 designates the base frame of the machine on which is mounted a standard 2 having a guide extension 3 upon the side portion thereof and to which are secured retaining strips 4. A shaft 5 is journaled in the upper end portion of the standard and secured to one end portion of this shaft is a disk 6 having a wrist pin 7 connected, by means of a pitman 8, to a plunger 9 mounted for reciprocation within the extension 3 and back of the strips 4. The lower end of the plunger 9 is reduced, to form a foot 10 adapted to move downwardly back of a stationary die 11. This die is seated in an angular recess 12 formed in the bottom portion of the standard 2, the upper front corner of the die 11 being overhung by a retaining lip 13 while any suitable means, such as a screw 14, may be extended into the die from the front wall of the recess 12 for the purpose of anchoring the die within the recess.

Die 11 has an inclined passage 13' the inner or lower end of which may be of any contour desired. In the drawings the die shown is designed to produce a bit having an offset point and, consequently, the bottom of the passage 13' is extended downwardly at the lower end of said passage, as shown at 15. If the front face of the point or offset end of the bit to be formed is to be flat, the inclined portion 15 of the bottom of the passage will also be flat, as shown in Fig. 6. If, however, a longitudinal groove is to be formed within the said offset portion of the bit, a bead, as shown at 16 in Fig. 5 will be provided along the inclined portion 15.

The top of the die 11 is covered by a plate 17 to which is secured a block 18 adapted to extend downwardly into the upper portion of the passage, as shown in Fig. 3. A presser foot 19 is also extended down into the passage 13', this presser foot having a stem 20 projecting upwardly therefrom and through a nut 21 which is screwed into the plate 17. This nut 21 constitutes an abutment for a spring 22 which is interposed be-

tween the nut and the foot 19 and serves to press the foot yieldingly in a downward direction. This downward movement of the foot is limited by a stop nut 23 or the like arranged adjustably on the upper end of the stem 20.

A feed chute 24 is extended forwardly and upwardly from the standard 2, the said chute alining with the passage 13' and having a slide 25 therein. This slide has a lug 26 which projects into a slot 27 formed within a lever 28, the said lever being fulcrumed, as at 29, upon a bracket 30 and there being a spring 31 connected to the lever whereby the slide 25 is held normally positioned in the outer end portion of the trough 24.

The plunger foot 10 carries a roller 32 which is adapted to travel close to or in contact with the back edge of the fixed die 11. A cutting tool 33 is seated in the foot 10 directly above the roller and is likewise adapted to travel close to the back surface of the die 11. This cutting tool is adjustably mounted, any suitable means, such as binding screws 34, being provided for holding it against movement after adjustment.

A shaft 35 is journaled within the lower portion of the standard 2 and below the die 11 and extending from this shaft is a stop arm or gage 36 adapted to be swung upwardly to position directly back of the passage 13' in the die 11. A crank arm 37 is secured to the outer end of the shaft 35 and is adapted to be actuated by hand. When this crank arm is swung upwardly the gage or stop arm 36 will be brought to any desired position relative to the die 11, the said gage or stop arm being preferably curved so that it can be brought to any desired distance from the rear face of the die 11. Upward movement of the gage or stop arm 36 can be limited by an adjustable stop pin 38 engaging a supporting bracket 39 depending from one of the retaining strips 4. This pin is preferably threaded as shown and holding nuts 40 engage the threaded portion and are disposed at opposite sides of the bracket 39.

A drive shaft 41 is journaled in suitable bearings 42 provided therefor and has a gear 43 which constantly meshes with a gear 44 mounted for rotation on the shaft 5. The gear 44 has a clutch member 45. Another clutch member 46 is feathered on the shaft 5 and has an annular groove 47 into which a holding pin 48 normally projects, this pin being held in normal position by a spring 49. A lever 50 has one end in engagement with the pin 48 while its other end is connected by a rod 51 to a foot lever 52. A cam 53 is formed with the clutch member 46 and a spring 54 is interposed between the standard 2 and the clutch member 46 so that, when the clutch member is released from the

holding pin 48, it will be shifted automatically into engagement with the clutch member 45.

A lever 55 is fulcrumed upon the upper end of the standard 2 and one end of this lever is connected by a yoke 56, to the upper end of the plunger 9 while the other end of lever 55 carries a weight 57.

In using the machine the proper die 11 is placed in its seat or recess 12 and the stop pin 38 is then adjusted so that, when arm 37 is raised, the gage 36 will be brought to a desired position relative to the back face of the die 11. Shaft 41 is then set in motion and gear 44 will be continuously driven, this gear rotating loosely on the shaft 5. The hot blank is then placed in the trough 24 and lever 28 is actuated so as to cause slide 25 to push against the blank and force it into the passage 13' where it will slide under the presser foot 19 and against the gage 36, it being understood that the gage is supported in raised position by the operator holding arm 37. The presser foot 19 will frictionally engage the blank to such an extent as to prevent said blank from sliding downwardly out of position within the passage 13' after the gage 36 has been lowered. As soon as the blank has been positioned, the arm 37 is released, thus permitting the gage to swing downwardly out of active position and lever 28 is also released so that spring 31 will return the said lever and slide 25 to their normal positions. The operator then presses downwardly on the foot lever 52 and this results in the withdrawal of the pin 48 from the groove 47. Consequently spring 54, which is under stress, will shift clutch member 46 into engagement with clutch member 45, thus coupling the shaft 5 to the rotating gear 44 and causing the pitman 8 to thrust the plunger 9 downwardly. The foot 10 of the plunger will move back of the die 11 and the roller 32 will engage the projecting portion of the blank and roll it downwardly into the inner end portion of the passage 13' so that an offset portion will thus be produced upon the blank. Furthermore, the cutting or trimming tool 33 which follows directly after the roller 32, will smooth off the inner end of the blank thus shaped and remove any surplus metal which may be protruding from the die 11. As soon as the foot lever 52 is depressed, the operator removes his foot therefrom so that the pin 48 will spring back against the clutch member 46 and in the path of the cam 53. Consequently, during the completion of the rotation of the clutch member 46, cam 53 will

ride upon the inner side of pin 48, thus forcing the clutch member 46 back against the spring 54 until groove 47 is brought into line with pin 48 whereupon said pin will spring up into the groove and thus lock 130

clutch member 46 in its set position. The weighted lever 57 will elevate plunger 9 to its uppermost position as soon as the clutch members have been disengaged from each other.

For the purpose of sharpening or reshaping used bits, a die such as shown in Figs. 7 and 8 may be employed. This die, which has been indicated generally at 57' 10 has one side wall of its blank receiving passage 58 formed of an adjustable block 59 within which is swiveled one end of a revoluble stem 60. Said stem extends through a bracket 61 secured to one side of the die 15 57' and a lug 62 extends radially from the stem and into a cam slot 63 formed in the bracket. An actuating arm 64 extends from the outer end of the stem 60 and by means thereof said stem can be rotated so as 20 to cause the lug 62 to travel within the slot 63. Consequently the block 59 will be shifted laterally so as either to increase or diminish the width of the passage 58. Thus it will be seen that, should it be desired to 25 sharpen or reshape a used bit which has spread at its active end, it would merely be necessary to shift the block 59 laterally so as to widen the passage 58 sufficiently to permit the insertion of the bit. Block 59 is 30 then shifted back toward its initial position so as to bind the bit against the opposed walls of the passage. Plunger 9 is then operated as before and the roller 32 and trimming tool 33 will operate in the manner 35 described.

It is to be understood that after a blank has been shaped in the manner hereinbefore described, a new blank can be placed in the trough 24 and pushed to position within the 40 die 11, this specially inserted blank operating to eject the formed bit from the die 11 and through the open space 65 formed in the bottom portion of the standard 2 and under the plunger 9.

45 What is claimed is:—

1. A machine of the class described including a stationary die, a plunger, a roller carried by the plunger for engaging a blank

projecting beyond the stationary die and rolling it upon said die, and a trimming 50 tool carried by the plunger and adjacent the roller.

2. In a machine of the class described the combination with a stationary die, of yielding means for automatically gripping and 55 holding blanks of different thicknesses within the die, a plunger, and a roller carried by the plunger for engaging one end portion of the blank to roll it upon the die.

3. In a machine of the class described, the 60 combination with a stationary die having a blank receiving passage formed with an offset portion, means for varying the width of said passage and means for feeding a blank into said passage and over the offset portion, 65 of a plunger, and a roller for engaging the blank to roll it into the offset portion.

4. In a machine of the class described, the combination with a stationary die having a blank receiving passage, and means for directing a blank into said passage, of a gage for limiting such movement of the blank, and means for engaging one end portion of the blank to shape it upon the die, said gage being movable into and out of the path of 75 said last named means.

5. In a machine of the class described, the combination with a stationary die, of means for feeding a blank onto the die, a gage for limiting the movement of the blank across 80 the die, automatic means for frictionally engaging the top of the blank to hold it against accidental movement irrespective of the thickness of the blank, a plunger, and a roller carried by the plunger for engaging 85 one end portion of the blank to roll it onto the die, said gage being movable into and out of the path of the plunger.

In testimony that I claim the foregoing as my own, I have hereto affixed my signature in the presence of two witnesses.
